FRANK K. LOW, OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed June 9, 1927. Serial No. 197,569.

This invention relates to telephone exchange systems, and more particularly to means in an exchange system employing machine switching apparatus controlled from a subscriber's substation dial, for enabling subscribers at substations remotely removed from a machine switching office to which its line terminates to control said apparatus accurately.

In most telephone systems, the exchange area is so divided into office areas that each office is located so that it is central to the subscriber's lines which it serves, and therefore the subscribers' lines are of substantially equal length and relatively short. The ohmic resistance and capacity of subscribers' lines is thereby made low so that the apparatus at the office which responds to impulses dialed by subscribers is enabled to respond accurately with a minimum of failure due to the impulses being mutilated during transmission over the subscribers' lines. It is not possible, however, to always so locate a central office, that no lines terminating therein shall be of greater length than is desirable for proper operation. This is particularly true of offices which serve suburban districts of exchange areas.

Where it is found necessary to serve a subscriber who is located at a considerable distance from an office, and whose line would consequently have considerable resistance, and capacity, it is desirable to provide more sensitive impulse responsive apparatus to receive the impulses dialed by the subscriber, and to repeat them to the selectors or other impulse recording apparatus of the office. This is particularly desirable, as then the precise adjustment of the subscriber's dial for sending impulses for the most efficient ratio of circuit closing and circuit opening periods is not so necessary. The present invention relates to a circuit which may be inserted at the exchange office between the external line extending to the subscriber's station and the internal line terminating in the usual exchange apparatus, whereby, regardless of the extent of mutilation of the impulses dialed either through the poor adjustment of the dial or through the attenuating effect of the line characteristics, the impulses repeated into the office appa-

ratus shall be of proper strength and character to accurately operate the apparatus of the office.

In accordance with the specific embodiment of the invention, chosen by way of illustration, the long subscriber's line is provided with a very sensitive impulse responsive relay which is adjusted to quickly and accurately follow the impulses dialed, and which in turn controls an improved impulse repeating relay. The impulse repeating relay has two windings, one, a primary or operating winding which is controlled directly from contacts of the impulse responsive relay, and the other, a secondary winding controlled through its own contacts and affected by the charging and discharging current through a condenser. The effect of the secondary winding as controlled by the condenser is such that should the operating make impulse through the primary winding of the relay be short, the charging current through its secondary winding and through the condenser will tend to hold the relay operated after the circuit of its primary winding is broken, for an interval predetermined by the capacity of the condenser, the number of turns in the secondary winding, and the resistance of the charging circuit, so that the make period of the impulse repeated by such relay will be longer than the make period of the impulse received over the subscriber's line. If, however, the make impulse received over the subscriber's line is long, the impulse repeated will be long also, since the repeating relay will not release until the operating circuit through its primary winding is broken.

On the other hand, when an open period occurs in the line circuit during dialing, the repeating relay deenergizes, providing a discharge path for the condenser through its secondary winding and back contact to ground through resistance, the direction of the discharge current being such that the flux set up is opposite in direction to the flux set up by the primary winding when the relay is energized. If, then, the open period between input impulses is too short, the repeating relay is retarded in operating following the open periods due to the opposing effect of the secondary winding,

and therefore the open period between the repeated impulses will be long. If the open period between the impulses received is long, however, the open period between repeated impulses will be long, but not longer than the period between received impulses, since by the time the primary circuit of the repeating relay is closed, the effect of the discharge current through the secondary winding will have subsided and the relay will no longer be delayed in operating.

Referring to the drawings for an illustration of the invention,

Fig. 1 shows a subscriber's line terminating at a machine switching office in a long-line equipment embodying the present invention; and

Fig. 2 discloses charts illustrating the manner in which the relay of the invention functions.

The subscriber's substation shown at 1 is of the usual type equipped with an impulse dial 2. The subscriber's line, having conductors 3 and 4, is assumed to be of considerable length having a maximum loop resistance which may be as high as 1700 ohms, and is shown terminating in special long line equipment at the central machine switching office. The long line equipment is shown at the right of Fig. 1 as being provided with the usual line and cut-off relays and with final selector multiples. The line conductors extending to the right margin of Fig. 1 may be terminated in a line finder bank and start circuit of the type disclosed in the patent to W. H. Matthies, No. 1,567,072, granted December 29, 1925. The exchange apparatus for extending connections from and to the calling subscriber's line may be of the well known type such as is disclosed in the patent to Matthies above referred to, and as disclosed in the patent to F. A. Stearn, 1,505,171, granted August 19, 1924. It is believed that the invention will be best understood from a detailed consideration of the circuit disclosed in Fig. 1 and from a description of the manner in which it functions.

When the calling subscriber at sub-station 50 removes his receiver from the switchhook to initiate a call, a circuit is closed for the impulse relay 5, which extends from battery through the right winding of relay 5, the lower left winding of repeating coil 6, the lower back contact of relay 7, over line conductor 4, through the substation 1, returning over line conductor 3, the upper back contact of relay 7, the upper left winding of repeating coil 6 to ground through the left winding of relay 5. Relay 5 energizes over this circuit, and at its front contact closes a circuit for the impulse repeating relay 8, extending from battery through resistance 9, the contact of relay 5, the left back contact of relay 10, to ground through

the left winding of relay 8. Relay 8 energizes and simultaneously closes both of its front contacts at its left contact closing a bridge across the internal line conductors 11 and 12, and through the winding of line 70 relay 13, which may be traced from battery through the winding of relay 13, the left back contact of cut-off relay 14, conductor 12, the lower right winding of repeating coil 6, the left contacts of relay 8, the upper 75 right winding of repeating coil 6, conductor 11 to ground through the right back contact of cut-off relay 14. The operation of line relay 13 causes, in the well known manner, the connection of the subscriber's line to a 80 district selector and sender in preparation for the selection of the desired line.

Upon the connection of the line to the district selector, battery becomes connected to the sleeve conductor 15, causing the energization of cut-off relay 14, which disconnects the line relay 13 and ground respectively from the conductors 12 and 11, and also causes the energization of relay 16 over a circuit from conductor 15, the right back 90 contact of relay 10 to ground through the winding of relay 16. Relay 16 upon energizing disconnects at its right back contact, the winding of relay 10, from the final multiple sleeve conductor 17, and at its front contact connects the sleeve conductor 17 through resistance 18 to battery, thereby marking the multiples of the subscriber's line as busy at the banks of all final selectors having access thereto. Relay 16 also connects the condenser 19 between the sleeve conductor 15 and the sleeve conductor 17 for the purpose of passing a checking tone if required, disconnects at its left back contact, the bridge across conductors 11 and 12 comprising the condenser 20 and ring-up relay 21, and at its left front contact connects the protecting conductor 22 and resistance 23 in series in bridge of the left or impulsing contacts of repeating relay 8 in preparation for repeating the dial impulses. At this time, a circuit has been extended through the left contacts of relay 8 and over conductors 11 and 12 into the district selector trunk circuit and thence to the impulse relay of the 100 selected sender in the manner described in the patent heretofore referred to.

The subscriber may now proceed to dial the number of the desired subscriber by manipulating his dial 2. Upon the first break in the loop circuit over conductors 3 and 4, relay 5 deenergizes quickly, opening the energizing circuit through the left winding of repeating relay 8. It is to be noted at this point that when relay 8 energized a 105 charging path was closed for the condenser 24, from battery through resistance 25, the right front contact of relay 8, condenser 24, to ground through the right winding of relay 8. This charging current flows 110

through the right winding of relay 8 in such a direction as to aid the left winding of relay 8. The right winding of relay 8 is without material effect upon the initial energization of relay 8. When now the initial energizing circuit of relay 8 is broken by relay 5, relay 8 releases, opening its front contacts and at its left contacts thereby releasing the pulsing relay of the associated sender. At 10 its right front contact relay 8 opens the charging path through condenser 24, and at its right back contact closes a discharge path for the condenser, which extends from ground through the right winding of relay 15 8, condenser 24, right armature, and back contact of relay 8 to ground through resistance 26. If the repeating relay 8 is not again energized within a definite time interval, the condenser 24 will thus become fully 20 discharged and the flux set up by the discharging current through the right winding of relay 8 will become entirely dissipated.

On the next closure or make of the dial contacts, relay 5 again energizes, in turn energizing relay 8 which again closes the bridge circuit across conductors 11 and 12. This operation continues as the dial 2 returns to normal upon each manipulation in accordance with the several digits of the 30 desired line number. When dialing is completed and the connection has been established to the line of the desired subscriber, relay 5 is maintained energized over the calling line and talking current is supplied 35 to the calling subscriber's substation through the left windings of repeating coil 6. Relay 5 holds relay 8 energized during conversation and these relays therefore function as supervisory relays under the control of the 40 calling subscriber.

In order that the impulse correcting functions of repeating relay 8 may be most clearly understood, it will first be assumed that the impulses as received by the relay 5 have 45 a minimum percentage of break interval to make interval, that is, that the intervals during which the subscriber's loop is closed between impulses are too long compared with the intervals during which the loop 50 is opened. In Fig. 2 two charts have been disclosed, the one at the left illustrating the condition assumed above. At the top of this chart the input impulses received by the relay 5 have been shown at A as having long make 55 periods as compared with the periods between impulses. Since the relay 5 follows very closely the impulses received, and repeats them correspondingly to the primary winding of relay 8, the current in the left 60 or primary winding of relay 8 will assume the general form shown at C. Upon each energization of relay 8, the condenser 24 charges through the secondary or right winding of the relay, causing a current in 65 the secondary winding, which, during a por-

tion of the time that the relay is energized over its primary winding, aids in the energization of the relay. During the open period between impulses, when there is no current flowing in the primary winding of relay 8; and the relay is deenergized, the condenser 24 is discharging, causing current to flow in the opposite direction through the secondary winding. The current through the secondary winding is thus in the form 70 shown at D. The resultant effect of the current in both windings of the relay is shown at E, the curve being a composite of the curves shown at C and D. It will be noted from an analysis of the curve E, that at the 80 points marked 200, the discharge of the condenser 24 through the secondary winding of relay 8 has opposed the primary winding of relay 8 since the break period between impulses was too short, and that the relay is 85 thereby delayed in reenergizing. The resultant impulses repeated by the left contacts of relay 8 therefore take the form disclosed at B, which form is far better for accurate 90 operation of the pulsing relay of the central office sender than the input impulses shown at A.

It will now be assumed that the impulses as received by the relay 5 have a maximum percentage of break interval to make interval, that is, that the intervals during which the subscriber's loop is closed between impulses is too short compared with the intervals during which the loop is opened. In the chart at the right of Fig. 2 this condition 95 has been illustrated. At the top of this chart the input impulses received by the relay 5 have been shown at A as having short make intervals as compared with the intervals between impulses. At C the curve of the current flowing through the primary winding of relay 8 has been illustrated as following accurately the input impulses. Again, upon each energization of relay 8, the condenser 24 charges through the secondary winding 100 of this relay thereby aiding the primary winding to hold the relay energized slightly after its primary circuit is broken and upon each deenergization of relay 8, the condenser 24 discharges in the opposite direction 105 through the secondary winding of the relay to oppose the primary winding. The curve of the current in the secondary winding is shown at D, and the resultant effect of the two windings is illustrated by the curve E. 110 It will be noted from an analysis of the composite curve E that since the periods during which the primary winding of relay 8 is energized are very short, that the secondary winding tends to set up a flux at 115 points 201, which is sufficient to hold the relay operated for an interval after each opening of the primary circuit. Since, in the case assumed, the break periods of the input 120 impulses have been assumed to be long com- 125

pared with the make periods, the condenser 24 has time to fully discharge each time that the relay 8 deenergizes before the primary circuit of the relay becomes again closed. 5 Thus the secondary winding has no effect upon the quickness with which the relay 8 energizes. The output impulses repeated by the relay 8 will therefore have the form indicated at B which, in comparison with the 10 input impulses shown at A, have their make and break periods more evenly divided. It is thus apparent that relay 8 acts to correct the form of the impulses received and to repeat them in a form which is better adapted 15 for accurate reception of the central station apparatus.

When the long line circuit shown in Fig. 1 is seized by a final selector, a busy condition is placed on the sleeve multiple 17 at 20 the final selector causing the operation of relay 10. Relay 10 upon operating disconnects, at its right back contact, relay 16 from the sleeve conductor 15, and connects the sleeve 15 over its right front contact through 25 resistance 18 to battery, making the line busy at the bank multiples of line finders in which it terminates. At its left armature contacts, relay 10 transfers the battery connection at the front contact of relay 5 from 30 the left to the right winding of relay 8, thereby reducing current drain during conversation.

When ringing current is applied to the tip and ring conductors 11 and 12 over the 35 final multiples from the incoming selector (not shown), relay 21 operates over a circuit which may be traced in part from conductor 11, the upper right winding of repeating coil 6, condenser 20, winding of relay 21, the left back contacts of relay 16, the lower right winding of repeating coil 6, to conductor 12. Relay 21 responds to the ringing current and at its contact closes an obvious circuit for relay 7. Relay 7 energizes upon each application of ringing current from the incoming selector, and at its 40 back contacts disconnects the windings of relay 5 from the line conductors 3 and 4, and at its front contacts extends the conductors 11 and 12 directly to the conductors 3 and 4 respectively, so that ringing current may pass directly over the subscriber's 45 external line to the substation bell. As soon as the subscriber responds, ringing current is 50 tripped at the incoming selector in the usual manner, whereupon relay 21 remains deenergized and relay 7 releases to reconnect the left windings of repeating coil 6 and the windings of relay 5 with the line conductors 55 3 and 4. Relays 5 and 8 now energize, talking current being supplied to the line from the repeating coil 6. Supervision is controlled by the bridge established at the left contacts of relay 8 and, through relay 5, is

under the control of the subscriber at sub- 65 station 1.

What is claimed is:

1. A relay having a primary and a secondary winding, an energizing circuit extending through said primary winding, a condenser, a charging path for said condenser extending through a front contact of said relay and through said secondary winding, and a discharge path for said condenser extending through the back contact of said relay and said secondary winding. 70 75

2. A relay having a primary and a secondary winding, an energizing circuit extending through said primary winding, a condenser, a charging path for said condenser extending through a front contact of said relay and through said secondary winding in such a direction as to cause said secondary winding to aid said primary winding, and a discharge path for said condenser extending through the back contact of said relay and through said secondary winding in such a direction as to cause said secondary winding to oppose said primary winding. 80 85 90

3. A relay having a primary and a secondary winding, an energizing circuit extending through said primary winding, a condenser, a battery, resistances, a charging path for said condenser extending from said battery through one of said resistances, a front contact on said relay and through said secondary winding, and a discharge path for said condenser extending through said secondary winding, a back contact on said relay, and through a second of said resistances to ground. 95 100

4. A relay, an energizing winding therefor, and means for rendering said relay slow to release only when its energizing circuit is closed for an interval shorter than a prescribed interval and for rendering said relay slow to energize only when reenergized after an interval shorter than a prescribed interval. 105 110

5. A relay, a primary winding therefor, an energizing circuit extending through said winding, a secondary winding, and means controlled by said relay for energizing said secondary winding in such a manner that said relay is rendered slow to release only when the energizing circuit of its primary winding is closed for an interval shorter than a prescribed interval and that said relay is rendered slow to energize only when reenergized after an interval shorter than a prescribed interval. 115 120

6. A relay, a primary winding therefor, an energizing circuit extending through said winding, a secondary winding, a condenser, and means controlled by said relay for charging and discharging said condenser through said secondary winding in such a 125

manner that said relay is rendered slow to release only when the energizing circuit of its primary winding is closed for an interval shorter than a prescribed interval, and that 5 said relay is rendered slow to energize only when reenergized after an interval shorter than a prescribed interval.

7. A relay, a primary winding therefor, an energizing circuit extending through said 10 winding, a secondary winding, a condenser, means controlled by said relay for charging and discharging said condenser through said secondary winding in such a manner that said relay is rendered slow to release only 15 when the energizing circuit of its primary winding is closed for an interval shorter than the charging time of said condenser, and that said relay is rendered slow to energize only when reenergized after an interval 20 shorter than the discharging time of said condenser, and means for controlling the

charging and discharging time of said condenser.

8. A relay, a primary winding therefor, an energizing circuit extending through said 25 winding, a secondary winding, a condenser, means controlled by said relay for charging and discharging said condenser through said secondary winding in such a manner that said relay is rendered slow to release only 30 when the energizing circuit of its primary winding is closed for an interval shorter than the charging time of said condenser, and that said relay is rendered slow to energize only when reenergized after an interval 35 shorter than the discharging time of said condenser, and resistances for controlling the charging and discharging times of said condenser.

In witness whereof, I hereunto subscribe 40
my name this 27 day of May, A. D. 1927.

FRANK K. LOW.
